UNITED STATES PATENT OFFICE.

FRED E. TWISS, OF LAWRENCE, MASSACHUSETTS.

DESIGN FOR A MONUMENT.

SPECIFICATION forming part of Design No. 36,239, dated February 24, 1903.

Application filed December 1, 1902. Serial No. 133,516. Term of patent 14 years.

To all whom it may concern:

Be it known that I, FRED E. TWISS, a citizen of the United States, and a resident of Lawrence, county of Essex, and State of Massachusetts, have invented a new, original, and ornamental Design for a Monument, of which the following description, in connection with the accompanying drawing, is a specification.

The single figure in the drawing is a front view of the monument, showing my new ornamental design.

As shown in the drawing, the leading or material feature of my design consists of three vertically-fluted pillars supported on a common base. Three interlocking ovals, representing the links of a chain, are supported at the upper ends of the pillars, one oval or link being supported on the top of each pillar. The representation of two clasped hands

is arranged across and in front of the middle pillar, and a wreath of leaves is also represented as supported in front of all three pillars. An open book is represented as supported on the base and leaning against the middle pillar.

Having thus described my invention, what I claim as new, and desire to secure by Letters Patent, is—

The ornamental design for a monument substantially as herein shown and described. 30

In testimony whereof I have signed my name to this specification in the presence of two subscribing witnesses.

FRED E. TWISS.
